UNITED STATES PATENT OFFICE.

EDWIN MOREY, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

WINDING MACHINE.

1,168,734.

Specification of Letters Patent. Patented Jan. 18, 1916.

Application filed May 8, 1913. Serial No. 766,300.

To all whom it may concern:

Be it known that I, EDWIN MOREY, a citizen of the United States, and resident of Nashua, New Hampshire, have invented an improvement in Winding-Machines, of which the following description, in connection with the accompanying drawings, is a specification, like characters on the drawings representing like parts.

This invention relates to machines for winding paper in the form of tubes and for other purposes.

The character of the invention may be best understood by reference to the following description of an illustrated embodiment thereof shown in the accompanying drawings, wherein:

Figure 1 is a front elevation of an illustrative winding machine shown herein as embodying the invention; Fig. 2 is a vertical section taken on line 2—2 of Fig. 1; and Fig. 3 is a vertical section taken on line 3—3 of Fig. 1.

Referring to the drawing, the illustrative machine shown therein as embodying the invention comprises a frame 1 associated with a paper pulp containing vat (not shown) containing a mold cylinder 3. Coöperating with the mold cylinder is a couch roll 5 and a web carrier 7. The above parts may be of usual well known construction and are adapted to form a web of paper from the pulp in the vat. The web of paper is conveyed by the carrier to a suction or base roll 9 of any suitable or usual construction. The web of paper may be transferred to and wound on a tubular mandrel 11 of aluminum or other suitable material.

The mandrel shown is of small diameter and considerable length and therefore is liable to bend axially and destroy the uniformity of the winding of the paper web thereon unless provision is made for maintaining the mandrel in straight axial alignment. To this end there is provided a presser roll 13 of substantial diameter and weight, said roll being journaled in bearings in a frame 15 on free ends of arms 17 pivoted to brackets 19 projecting from the machine frame.

An important feature of the invention relates to the relation of this presser roll with the mandrel. As shown herein, the mandrel base roll is rotated in a contra-clockwise direction and the mandrel is frictionally ro-

tated thereby in a clockwise direction. The presser roll is mounted to bear on the mandrel at a line offset somewhat from the left (Fig. 2) of a straight diametrical line common to and passing through the base roll 60 and mandrel centers. Tangent lines, if drawn through the points of contact of the mandrel with its base and presser rolls, would converge to the left of said figure. The mandrel in rotating tends to work itself 65 toward the apex formed by said tangents and thereby tends to crowd itself in between the base and presser rolls, and prevents any bellying of the mandrel or departure thereof from straight axial alinement. The use of a 70 single presser roll in preventing distortion of the mandrel is extremely advantageous, since the roll contacts with the soft paper pulp being wound on the mandrel along but one line of contact, and thereby a uniform 75 pressure is maintained on the mandrel tending to produce a paper tube of uniform compactness and consistency throughout.

The rotating of the cylinders and rolls described will wind the paper web on the 80 mandrel until a desired thickness of tube or material is obtained. On the occurrence of this event it is desirable to remove the mandrel from its active winding position between the base and presser rolls and to substitute an empty mandrel therefor.

An important feature of the invention relates to mechanism for shifting the mandrels to and from active winding position. To this end there is provided a carrier 21 90 comprising spaced elongated heads 23 fast on a shaft 25 journaled in bearings in the frame 1, said heads being provided with bosses 27 in which are journaled shafts 29. Fast on these shafts are arms 31 having 95 suitable provision for detachably supporting the mandrel 11, referred to, between their free ends. As shown herein, the carrier is provided with two sets of diametrically opposed arms such as described for supporting two mandrels, one in active and the other in inactive position. It will be understood, however, that the carrier may be equipped to accommodate any desired 100 number of mandrels. The carrier is rotated at appropriate intervals to withdraw one of the mandrels from active winding position and substitute an empty mandrel therefor. To this end the carrier shaft 25 is provided 105 adjacent one end thereof with a friction disk 110

35 (Fig. 1) fast thereon coöperating with a second friction disk 37 loose on a reduced portion of said shaft. The disks 35 and 37 are constructed and arranged with appropriate means tending to press the same into intimate frictional engagement. To continuously drive the disk 37 there is provided a large sprocket wheel 39 driven by a chain 41 from a smaller sprocket wheel 43 fast on 10 a shaft 45 journaled in bearings in the machine frame. To rotate the shaft 45 it is provided with a large sprocket wheel 47 driven by a sprocket chain 49 from any appropriate source of power.

15 Since the friction disk 37 is continuously rotated it will continuously tend to rotate the friction disk 35 and the shaft and mandrel carrier. The carrier must be locked against rotation while the mandrel is being 20 wound. To this end the carrier is provided with an end plate 51 (Fig. 2) having a notch at its lower end coöperating with a locking lug 53 on a sliding plate 55 supported on the machine frame by pins 57 entered through elongated slots 59 in said plate. The locking plate is normally held up to present the lug 53 in locking engagement with the plate notch by a helical spring 61 interposed between the lower end of said 25 plate and a bracket 63 projecting laterally from the frame 1. By moving the locking plate downward the lug 53 will release the plate 51 and the carrier will be rotated in a contra-clockwise direction (Fig. 2) by its 30 frictional driving mechanism described.

As shown herein, means is provided for automatically releasing the lock lug by the movement of the mandrel arm 31 as it is rocked upward by the increase of material 40 wound thereon. To this end each rocking mandrel arm is provided with a dog 65 (Fig. 2) for engagement with an arm 67 fulcrumed on a pin 69 carried by a bell crank lever 71 fulcrumed on a pin 73 projecting 45 from the frame 1. One arm of this bell crank lever is provided with an elongated slot 75 for receiving a pin 77 projecting from the lock plate for a purpose to be described. The rocking movement of the arm 50 67 is transmitted by an adjusting screw 79 to a lever 81 also pivoted on the pin 69, said lever in turn being provided with an adjusting screw 83 for engagement with a dog 85 pivoted on a pin 87 projecting from the lock 55 plate 55 referred to.

Continuously rotated adjacent the end of the dog 85 is an arm 89 fast on the shaft 45 referred to. When a predetermined amount of material has been wound upon the active 60 mandrel 33 its supporting arm 31 will have rocked sufficiently to cause its dog 65 to engage the arm 67 and rock the latter, this movement being transmitted to the lever 81 through the screw 79. The lever 81 then 65 rocks the dog 85 into the range of the con-

tinuously rotated arm 89. On the occurrence of this event the arm 89 will engage the dog 85 and operating through the latter, will slide the locking plate 51 downward against the resistance of its spring, thereby 70 releasing the lug 53 from the locking plate notch and permitting the mandrel carrier to be rotated by its frictional driving means to withdraw one of the mandrels from active 75 position and introduce another of said mandrels into active position.

The mandrel carrying arms are free to swing on the carrier. Therefore, in the course of the rotation of the carrier in shifting the mandrels, said arms would tend to 80 swing and depend downward. As a result, the filled mandrel might drag objectionably along the surface of the web on the roll, with liability of injuring the soft paper tube on said mandrel. It is, therefore, desirable 85 to positively control and guide the mandrel swinging arms in the course of the rotation of the carrier. To this end each of the mandrel arm shafts 29 is provided with a controlling arm 101 (Fig. 3) having at its 90 free end a roller 103 received in and guided by a withdrawal cam slot 105 and an introduction cam slot 107 in a plate 109 at one end of the carrier and secured to the machine frame. The entrance end of the withdrawal cam slot 105 is so formed that on the initial rotation of the carrier the mandrel is immediately lifted up out of engagement with the base roll. The continued rotation 95 of the carrier will cause the mandrel to be 100 guided thence to the position shown at the left of Fig. 3 at the front of the machine. Here the mandrel is readily accessible and may be manually removed from its arms and an empty mandrel substituted therefor. 105 After an empty mandrel has been placed on the arms the latter are manually swung over to present the mandrel in the position shown in dotted lines at 111 (Fig. 3). In this position the guide roller is at the entrance 110 throat of the introduction cam slot 107 in readiness to be guided by the latter into active position for winding on the next rotation of the carrier. Thus the rotation of the latter simultaneously automatically withdraws a full mandrel from active position 115 and substitutes an empty mandrel therefor. Before a mandrel can be shifted to and from active position the presser roll should be lifted out of engagement therewith. To 120 this end the presser roll frame 15 (Figs. 2 and 3) is connected by vertical rods 113 with levers 115 fulcrumed on the shaft 45 referred to. To rock these levers and lift the presser roll up out of engagement with the 125 mandrel they are extended beneath cams 117 having flat faces 119, said cams being mounted fast on a shaft 121 journaled in bearings in the machine frame and paralleling the shaft 45 referred to. To drive the shaft 121 130

the shaft 45 is provided with a spur gear 123 fast thereon driving a gear 125 loose on the shaft 121. To transmit the drive from the gear 125 to the shaft 121 they are provided with coöperating friction disks 127 and 129 (Fig. 1).

To normally lock the shaft 121 against rotation it is provided at one end thereof with a dog 131 (Fig. 2) engaging a lug 133 projecting laterally from the lock plate 55 referred to. When the lock plate is slid downward as described, first the lug 133 will escape beyond the end of the dog 131, thereby permitting the shaft 121 and the 10 cams thereon to rotate, causing said cams to engage the levers 115 and tilt them, thereby lifting the rods 113 and the presser roll 13 up out of engagement with the mandrel.

Continued downward movement of the lock plate will cause the lug 53 to release the carrier plate 51, thereby permitting the carrier to be rotated by its frictional driving mechanism to shift a filled mandrel from 20 winding position and substitute an empty mandrel therefor as described. In the course of this shifting movement the lug 53 is pressed by the spring 61 into engagement with the edge of the carrier 51 which is 25 formed to permit the upward movement of the lock plate under the action of said spring and thereby bring the lug 53 in position to catch into a diametrically opposite notch of the lock plate and limit the rotation of the carrier. The notches in the carrier plate 30 thus serve to determine the active winding position of the mandrel. The carrier is held firmly against one or the other of the lugs by the tendency to drive the carrier shaft 35 continuously through the friction disks 35 and 37 referred to.

The carrier with its swinging mandrel arms or members constitute articulated means, the mandrel members of which are 40 guided and controlled in their shifting movements by the cam slots as described.

In order to permit tubes of varying thickness to be wound the screws 79 and 83 may be adjusted to cause the mandrel operated 45 dog 15 to engage the arm 67 earlier or later as desired.

To prevent interference by the arm 67 with the mandrel arm operated dog 65 in the retreat of the mandrel from active position the bell crank 71 is rocked about its pin 73 as a fulcrum to move the arm 67 out of range with the dog 65, this movement being effected by the sliding of the pin 77 in the elongated slot 75 of said bell crank 55 when the lock plate is slid downward to release the locking lug 53 from the carrier plate 51. Since the carrier cannot rotate until the locking plate has been moved down the preventing of interference with the dog 60 65 is assured.

By this invention there is provided a simple and effective mechanism for automatically withdrawing a filled mandrel from active winding position and substituting an unfilled mandrel therefor. The mounting 70 of the mandrel on swinging arms pivoted on the carrier relieves the mandrel from the burden of supporting a heavy mechanism for shifting it and enables the free swinging movement of said arms as the pulp layer 75 accumulates thereon.

By the construction and arrangement of the presser roll 13 the mandrel is maintained in straight axial alinement and thus is pressed equally by said presser roll throughout its length. On the completion of the winding of the pulp on a mandrel the presser roll is automatically, mechanically lifted out of engagement with the mandrel by a simple and effective mechanism.

While the invention has been described herein as embodied in a paper tube winding machine, it will be understood that it is not limited thereto, but is obviously applicable to machines for other purposes.

Having described one illustrative embodiment of the invention, without limiting the same thereto, what I claim as new and desire to secure by Letters Patent is:

1. A machine of the class described comprising, in combination, mandrels; means for winding material thereon; a mandrel carrier; arms pivoted to the latter for supporting said mandrels; and means for actuating said carrier to move the mandrels to 95 and from winding position.

2. In a machine of the class described, the combination of a carrier; mandrel supporting arm thereon; and means for actuating said carrier to move said arms progressively 105 to active position; and means controlled by movement of one of said arms for initiating such actuation of said arms.

3. In a machine of the class described, the combination of a carrier; mandrel supporting arms pivoted thereon; means for turning said carrier to move said arms successively to active position; guide means for said arms; locking means for said carrier; and means operated by said arms for releasing 110 said locking means to permit rotation of said carrier.

4. In a machine of the class described, the combination of a carrier; mandrel supporting arms supported thereon; frictional driving means tending to rotate said carrier; locking means to prevent rotation of said carrier; cam guides for controlling the shifting movements of said arms; and means for automatically releasing said locking means 115 to permit the rotation of said carrier.

5. In a machine of the class described, the combination of a carrier; mandrel receiving arms thereon; means for turning said carrier to shift the arms to and from active 120 125 130

position; guides; and arms connected to said mandrel arms and coöperating with said guides to control the shifting movements of said arms.

5. 6. In a machine of the class described, the combination of a carrier; shafts journaled therein; mandrel supporting arms on said shaft; cam guide means; means on said shafts coöperating with the latter for controlling the movements of said arms; and means for rotating said carrier to move one of said arms out of active position and another of said arms into active position.

10. 7. In a machine of the class described, the combination of a carrier; mandrel receiving arms thereon; means for rotating said carrier to shift said arms; means for locking said carrier against rotation; and trip means operated by said arms for releasing said lock.

15. 8. In a machine of the class described, the combination of a carrier; swinging mandrel arms thereon; a base roll supporting one of said mandrels; a presser roll for the latter; and means controlled by increase of material on said mandrel for lifting said presser roll

from such mandrel and for shifting said mandrels to and from active position between said base and presser roll.

9. In a machine of the class described, the combination of a base roll; a mandrel; and an alining presser roll for said mandrel having provision for supporting the same offset from a diametrical line passing through the centers of said base roll and 35 mandrel.

10. In a machine of the class described, the combination of articulated means comprising members pivotally connected; means for supporting mandrels on some of said 40 members; means for actuating said articulated means to shift said mandrels to and from active position; and guide means for controlling said mandrel carrying members in the course of their shifting movements. 45

In testimony whereof, I have signed my name to this specification, in the presence of two subscribing witnesses.

EDWIN MOREY.
